UNITED STATES PATENT OFFICE.

JOHN MURRAY, OF EDINBURGH, SCOTLAND.

LOOSE-LEAF BOOK.

1,243,544.

Specification of Letters Patent.

Patented Oct. 16, 1917.

Application filed March 2, 1917. Serial No. 152,031.

To all whom it may concern:

Be it known that I, JOHN MURRAY, a subject of the King of Great Britain and Ireland, and a resident of Edinburgh, Scotland, have invented certain new and useful Improvements in Loose-Leaf Books, of which the following is the specification.

The invention relates to "loose-leaf" books and binders of the type in which pins secured in the binding cover pass through perforations in the leaves; and the invention has for its object to provide a "loose-leaf" book in which the various disabilities of existing binders are obviated, in which there are no complex locking devices and in which the insertion and removal of leaves is a matter of the greatest simplicity.

According to the invention the improved binding device comprises essentially a cover the back of which is of sufficiently rigid construction to serve as a guide. Coacting with guiding surfaces on either internal side of this back are rails having projecting pins engaging apertures perforated as usual in the loose leaves of the book, which rails lie on either side of the inner or back edge of the assembled leaves. Stops are provided in the back to limit the travel of the rails with the leaves therein, and a locking or clip device may be provided to retain them in position. Means are provided for retaining the rails at such a distance apart (irrespective of whether there be a full complement of leaves) that they snugly fit the guides in the back. The back may be curved or flat, and is fitted with a case of cloth or other material after the manner of a book cover.

An example of the carrying out of the invention is shown upon two accompanying sheets of explanatory drawings, Figures 1 and 2, Sheet 1 being respectively an end elevation of the sheet metal back and leaf retaining rails, and an end elevation of an assembled volume, while Fig. 3 shows in end elevation an alternative form of sheet metal back. Figs. 4 and 5, Sheet 2, are respectively a sectional elevation of leaves assembled upon the rails and a vertical sectional elevation of a completed volume.

According to this simple illustrative example, the back A of sheet metal is ovoid in section, the edges B being inturned to form guides for the rails C which are of sub-

stantially semicircular section. A block D filling one end of the back (Fig. 5) closes 55 the guides B and so determines the position of the rails C when they are pushed home. At the other end of the back the space behind the guides is filled by a similar block E. Instead of the guide edges B stopping 60 abruptly as shown in Fig. 1, they may be out-turned as shown in Fig. 3 to form grooves in which the usual cover jointing strips are held—thus avoiding any tendency for these strips to be torn off when the 65 book is opened.

On the rails C, and as to be seen most clearly in Fig. 4, are pins G passing through the leaf apertures. The outer ends of the pins on one rail butt into recesses H formed 70 in the other rail and thus determine the width between the rails. The covers J are are mounted upon the back in usual bookbinders' fashion, the back being also covered and finished in any desired manner. 75

Alternatively, the rails with the leaves may be adjusted to fit the guides in the back by the insertion of some form of filling either outside or inside the rails.

In order that the completed book may 80 open flat or substantially so at any part, the pins on the rails may be curved. Or flexible pins, formed for example of closely wound helical coils, may be used. Any convenient form of catch or lock may be provided to 85 prevent withdrawal of the filling from the back.

What I claim is:—

1. A "loose-leaf" book device comprising a cover the back of which is of sufficiently 90 rigid construction to serve as a guide, guiding surfaces on either internal side thereof, rails one on either side of the assembled leaves and coacting with the guiding surfaces, projecting pins on the rails engaging 95 apertures in the loose leaves, and means to limit the travel of the rails in the back and to determine the width between the rails, as set forth.

2. A "loose-leaf" book device comprising a 100 cover the back of which is of sufficiently rigid construction to serve as a guide, guiding surfaces on either internal side thereof, rails on either side of the assembled leaves and coacting with the guiding surfaces, projecting pins on the rails engaging 105 apertures

in the loose leaves, filler blocks at the opposite ends of the back, one of said blocks being larger than the other and extending into the guide ways to close the latter at one end 5 of the back, and recesses in each rail into which the outer ends of the pins butt as set forth.

In testimony whereof I have signed my name to this specification, in the presence of two subscribing witnesses.

JOHN MURRAY.

Witnesses:

FREDERICK PIATT,
HELEN SUTHERLAND.
